UNITED STATES PATENT OFFICE.

RICHARD SUNDERMAN, OF NEW YORK, N. Y., ASSIGNOR TO JOHNSON AUTOMATIC SEALER CO., LTD., OF BATTLE CREEK, MICHIGAN, A PARTNERSHIP ASSOCIATION LIMITED OF MICHIGAN.

CARTON OR CONTAINER.

Application filed October 11, 1921. Serial No. 506,957.

To all whom it may concern:

Be it known that I, RICHARD SUNDERMAN, a citizen of the United States, and resident of New York, N. Y., have invented new and useful Improvements in Cartons or Containers, which invention is fully set forth in the following specification.

This invention relates to containers or cartons and more particularly to cartons having tucked-in closure flaps and the sealing of the same.

Heretofore, cartons or containers for cereals and other food products have generally been provided with side and end top closure flaps folded one over the other and sealed in the usual manner. Cartons of this type have generally required the use of a paper bag or liner for containing the cereal or other food material and protecting the same after the package has been opened. Lined cartons of this type are expensive, and one of the objects of the present invention is to provide a carton or container which is more economical to produce in that it embodies less carton material, which may be effectively and readily sealed at the factory and which, after the seal has been broken by the consumer, may be effectively and readily closed by the latter to protect the contents between periods of use without the use of a liner and by the provision of tucked-in closure flaps.

In addition, the sealing flap or closure is so constructed and arranged as to be utilized as a pulling tab. This is of particular importance in the packaging of shoes and the like where it is the customary practice to store opened packages on shelves in stacks or tiers, and where removal of the same is often difficult and time-consuming. Such packages generally comprise rigid box-like structures having separate lids or closures and, due to constant handling, the lids and even the boxes become broken or otherwise rendered unfit for use, necessitating replacement involving inconvenience and additional expense. In addition to losses thus incurred, such containers are costly and, prior to filling occupy valuable storage space which could be utilized for other purposes.

In this aspect, a further object of the invention is to provide a container which is

of simple construction and inexpensive to manufacture, which may be readily assembled, filled, and closed by machinery and methods now in use for similar purposes, and which overcomes the defects and disadvantages of containers heretofore used for this purpose by providing a container having a tucked-in closure flap and a portion sealable thereover to prevent accidental or unauthorized removal of the tucked-in closure flap, the same sealing means being later utilizable as a pulling tab for readily removing the container from a shelf or other storage space.

Preferably, the invention comprises a collapsible tubular container of general rectangular form and constructed from a single blank of material providing side walls, flaps forming continuations of said side walls and adapted to be folded one over the other to thereby constitute end walls for the container, one of the flaps providing a hinged tucked-in closure, and one of the continuations providing one or more flaps adapted to be sealed over said tucked-in closure flap after assembly of the blank and providing a pulling tab or tabs after the container has been opened.

The invention is capable of receiving a variety of mechanical expressions, some of which are shown in the accompanying drawings, but it is to be expressly understood that the drawings are for purposes of illustration only and are not to be construed as a definition of the limits of the invention, reference being had to the appended claims for that purpose.

In said drawings:—

Fig. 1 is a longitudinal sectional view of one embodiment of the invention, the same being taken on line 1—1 of Fig. 4;

Fig. 2 is a plan of the blank from which the container shown in Fig. 1 is made;

Fig. 3 is a perspective view of several containers embodying the present invention and arranged in stacks or tiers on a shelf or other support;

Fig. 4 is a transverse sectional view of the container taken on the line 4—4 of Fig. 1; and

Figs. 5, 6, 7, 8, 9 and 10 are fragmentary perspective views of other containers embodying the present invention.

2

Referring to the drawings and more particularly to Figs. 1 and 2, the container comprises a collapsible tubular body of rectangular cross section having longitudinal side walls 1, 2, 3, 4 and end walls which are adapted to close opposite ends of the tubular body and which include end flaps 5 and 6, respectively, one or both of which may constitute hinged closures providing for insertion and removal of articles or materials within the container, the end flap 5 being provided with a tongue 15 which is tucked in the container adjacent the side wall 4. One of the walls herein shown as wall 4 is continued to provide a projecting flap 7 smaller than the end forming part of flap 5. Flap 7 is folded over the tucked-in portion 15 and sealed on the closure flap 5 after the container has been filled. The package may be opened in any suitable manner, as by inserting a knife or other suitable instrument under the edge of the flap 7, whereby the tucked-in closure may be removed and access had to the contents of the packages. After the package has been unsealed the flap 7 may be utilized as a pulling tab whereby the package may be readily removed from a shelf or other place of storage, the tucked-in closure flap 5 protecting and preventing loss of the contents of the package. Containers embodying the present invention as above described are designed principally for packaging materials such as cereal, coffee, and other food products, but they may also be utilized for packaging articles such as shoes, and the like, and, referring to Fig. 3, packages containing such articles may be opened on receipt of the same from the manufacturer and stored in stacks or tiers on a shelf 8 or other suitable support, the unsealed flaps 7 providing pulling tabs whereby individual packages may be readily removed from stacks or tiers of other packages.

The container illustrated in Figs. 1 to 4 inclusive is preferably formed from a folded blank of paper or other suitable material, and, referring to Fig. 2, the longitudinal walls 1, 2, 3, 4 of the container constitute subdivisions of the blanks as indicated by dotted lines in the figure, the subdivision constituting the wall 4 being continued to form on the outer longitudinal edge thereof of a sealing flap 9 adapted to provide an abutment for the side wall 1 when the blank is folded and sealed to form the main tubular body portion of the container.

The subdivisions of the blank are each continued at one end to provide respectively end flaps 10, 5, 11, and the projecting sealing and pulling flap 7, and said subdivisions are each continued at the opposite end to provide respectively end flaps 12, 6, 13 and 14, said end flaps constituting end walls for the container when the blank is folded, as

shown in Figs. 1 and 4. The flaps 10, 11 and the flap 5 provide respectively inner and outer plies for one of the end walls and the flaps 12, 13, and the flap 6, provide inner and outer plies respectively for the opposite end wall, the flap 14 providing an intermediate ply for a purpose hereinafter described. The various sub-divisions of the blank are bent to form the tubular body, as will presently appear, and the flaps have imperforate connections with said body so that weakening of the same when folded is avoided.

The end flap 5 is of greater length than the others and terminates in a portion providing a bendable tongue 15 which, after assembly of the blank and filling of the container, is inserted or tucked within the container between adjacent edges of the end flaps 10, 11 and the wall 4, the end flap 5 and tongue 15 providing a hinged tucked-in closure whereby materials or articles may be inserted within the container. The flap 7 adjacent the tucked-in portion 15 of the closure flap is utilized to seal the package as above described.

The containers embodying the present invention may be assembled by any suitable machine adapted to bend the blanks into tubular form and glue the sealing flap 9 to the wall 1 at the free longitudinal edge thereof, the tubular containers thereafter being collapsed with their flaps extended, and stored for use until needed for packaging purposes. It will appear obvious that quantities of containers can thus be stored in a limited space, thus overcoming the objection to other containers heretofore used, the construction of which requires the occupation of valuable storage space which could be utilized for other purposes. When it is desired to package materials such as cereals, coffee or other food products, or articles such as shoes and the like, the containers may be closed at one end by placing the same on formers adapted to feed the containers past well known flap folding and glue applying mechanisms, and to this end the above described container is provided with the intermediate ply or flap 14 which is folded over the flaps 12 and 13 and over which the flap 6 is folded and sealed in the usual manner. The container is then filled, either by machinery or by an attendant, and subsequently closed by folding in the end flaps 10, 11, the flap 5 then being folded over the flaps 10 and 11 and tucked within the container as previously described. The operations of the folding in the flaps 10 and 11 and tucking in the closure flap 5, may be performed by machinery or by an attendant, and the packages may be sealed in the usual manner by machinery adapted to fold and seal the flap 7 to the closure flap 5. By this method quantities of containers may be assembled

and filled, the machines only requiring a single attendant.

Referring to Figs. 5 to 10 inclusive, which illustrate other embodiments of the present invention, 7', 7'', 7''' indicate respectively different forms of sealing and pulling flaps, forming parts of blanks (not shown) which are slightly different from the blank illustrated in Fig. 2. The constructions shown in these figures are otherwise the same as the construction shown in Figs. 1, 3 and 4, and the manner of assembling, filling and sealing the containers is identical with similar operations performed in connection with the embodiment described above. The flaps 7', 7'', 7''' may be utilized as pulling tabs after they are unsealed to open the respective containers and are particularly adapted for the display of advertising or other matter.

It will appear obvious that packages not requiring sealing may embody certain characteristics of the present invention, particularly the flap 7 which may be utilized alone as a pulling tab whereby individual containers may be readily removed from a place of storage such as a shelf or other suitable support when the same are arranged singly or in stacks or tiers on the support.

From the foregoing disclosure it will be apparent that the invention provides an efficient and inexpensive container which does not require the use of any special machinery or methods in the manufacture thereof, and it will appear obvious that changes in the construction and arrangement of parts, such as elimination of the sealed end wall and the substitution therefor of a hinged closure, may be made without departing from the invention, such changes being intended to fall within the scope of the invention defined in the appended claims.

What is claimed is:

1. A container for packaging articles or materials comprising a tubular body provided with a closure flap having a portion insertible within the container, and means for sealing the container after the latter has been filled and closed, said means comprising a flap adapted to be sealed on said closure flap over the portion thereof inserted within the container, said sealing means having an imperforate connection with the tubular body and providing a pulling tab after the container has been opened.

2. A collapsible tubular container for packaging materials or articles formed from a single blank of material, closing and sealing means for said container forming a part of said blank, said means comprising a flap having a portion thereof inserted within the container after the latter has been filled and closed and a flap having an imperforate connection with the container adapted to be

sealed on said closure flap over the inserted portion and providing a pulling tab after the container has been opened.

3. A container having a tucked-in closure flap, and sealing means comprising a flap 70 having an imperforate connection with the container adapted to be sealed on said closure flap and providing a pulling tab after the package has been opened.

4. A collapsible tubular container of 75 rectangular cross-section comprising longitudinal side walls and transverse end walls, said end walls comprising outer and inner plies composed of superimposed folded flaps, one of said flaps constituting a hinged insertible closure for the container, and a pulling tab having an imperforate connection with one of said side walls and forming a continuing extension of the same.

5. A blank for making tubular containers comprising a single sheet of material subdivided to provide side walls for the container when the blank is assembled, the material of said subdivision being continued beyond the ends thereof to provide flaps constituting end walls for the container, one of said flaps constituting a closure flap and having a portion insertible within the container and an alternate flap having an imperforate connection with the main body of 90 the blank and adapted to be sealed on the closure flap over the insertible portion thereof and providing a pulling tab when unsealed.

6. A carton provided with a closure flap 100 having a part inserted within the carton and a part substantially forming one end of the same, and a flap smaller than the end forming part of the closure flap, sealed thereon over the inserted part and serving as a pulling tab when unsealed.

7. A carton comprising a tubular body provided with a closure flap having a part insertible within the body and a part substantially forming one end of the carton 110 when the same is closed, and a flap smaller than the end forming part of the closure flap having an imperforate connection with the tubular body and adapted to be sealed on the closure flap over the insertible part thereof, said smaller flap serving as a pulling tab when the same is unsealed.

8. A carton provided with a closure flap having a bendable tongue insertible within the carton and a part substantially forming one end of the carton when the same is closed, and a flap smaller than the end forming part of the closure flap adapted to be sealed thereon after said tongue has been inserted within the carton, said smaller flap serving as a pulling tab when unsealed.

9. A rectangular carton having at one side a closure flap provided with a tongue insertible within the carton and a part substantially forming one end of the carton 120

when the same is closed, and a flap at the opposite side of said carton smaller than the end forming part of the closure flap adapted to be sealed thereon when said tongue has been inserted within the carton, said smaller part serving as a pulling tab when unsealed.

10. A rectangular carton comprising a tubular body having at one side a closure flap provided with a tongue insertible within the carton and a part substantially forming one end of the carton when the same is closed, and a flap at the opposite side of the carton having an imperforate connection with the tubular body and adapted to be sealed on the closure flap over said tongue when the same is inserted within the carton,

said smaller flap serving as a pulling tab when unsealed.

11. A rectangular package including a body provided at one side with a closure flap having a tongue inserted within said body and a part substantially forming one end of the package, and a flap at the opposite side of said body smaller than the end forming part of said closure flap and sealed thereon over the inserted tongue, said smaller flap serving as a pulling tab when unsealed to open the package.

In testimony whereof I have signed this specification.

RICHARD SUNDERMAN.
